INSULATED ELECTRODE CONSTRUCTION
FOR SPARK PLUGS

Hector Rabezzana, Flint, Mich., assignor to General Motors Corporation, Detroit, Mich., a corporation of Delaware

Application July 18, 1934, Serial No. 735,725

3 Claims. (Cl. 123—169)

My invention relates to spark plugs for internal combustion engines, and particularly to center wire or insulated electrode features of such devices which electrode is supported by 5 and extends through a passage in the insulator of the plug.

It is of extreme importance in spark plugs that expansion of the insulated electrode shall not crack or otherwise injure the insulator, to 10 which end the inner part of the insulated electrode extends loosely through a passage provided for it, but is not cemented within said passage; so that said inner part is free to expand and contract without subjecting the insulator to 15 strain due to differences in expansion between the metallic electrode and the insulator, which is commonly made from porcelain or equivalent ceramic material.

Porcelain and equivalent material insulators 20 are provided with a longitudinally extending passage for the center wire which has to be formed before the insulators are subjected to the usual firing operation; and they are often distorted during the firing so that the passage, 25 though initially straight, is often more or less crooked after firing. A further object of my invention therefore contemplates an insulated electrode which may be placed within a more or less crooked passage without subjecting the insulator to strain and perhaps cracking it; and to this end the center wire or insulated electrode is made in two parts so that each may adapt itself to the portion of the passage through which it extends. The inner part of this insulated 30 electrode passes loosely through the inner part of the passage and need be but slightly smaller in diameter than the passage, whereas the outer part thereof is cemented in place within the outer part of the passage; the lower end of the outer part of the electrode abutting against, but not being mechanically connected with, the upper end of the inner part of the electrode.

The lengths of the two parts which form the center wire or insulated electrode are such that 45 the lower end of the upper part abuts against the upper end of the lower part at a point within the enlarged central part of the insulator, which central part is held within the external metallic shell or casing of the plug and whereby a further feature of advantage in spark plugs is secured; the same being a more effective dissipation of heat from the upper end of the lower electrode part to a massive central part of the 50 insulator, and from said part and by as short

and direct a path as is possible to the external shell or casing of the plug.

The above and other features of advantage in spark plugs are secured by the structural features illustrated in the accompanying drawing, 5 although my invention may be embodied in other forms than the particular one illustrated; and I therefore regard my invention as including such variations and modifications of the particular form illustrated as come within the scope 10 of the concluding claims wherein the features wherein my invention consists are particularly pointed out.

My invention as disclosed and claimed in this present application is in the nature of an improvement in one of the forms of insulated electrode or center wire construction disclosed and claimed in my application Serial Number 676,996 for a Spark plug, filed on June 22, 1933.

In the drawing:

Figure 1 is a view showing a section upon a central longitudinally extending plane, of a spark plug having center wire or insulated electrode features in accordance with my invention.

Figure 2 is a perspective view showing a finished flat metallic blank before it is bent into tubular form to provide a tubular terminal and holding member.

Figure 3 is a perspective view of a tubular terminal and holding member formed by bending the blank illustrated in Figure 2 into tubular form.

Referring now to the drawing for a more complete understanding of my invention, the numeral 4 designates the external metallic shell 35 or casing of a spark plug; and 5 the insulating member thereof made of porcelain or equivalent material and which is secured within the shell in any way, as by an inturned flange 6 of the shell. This insulating member has an enlarged 40 central portion as shown, and suitable gaskets 7, 8 are provided at the upper and lower ends of the enlarged part as is usual in spark plugs.

The insulating member is provided with an internal ledge 9 within its enlarged central part; 45 with a lower electrode passage 10 leading from said ledge to the inner end of the insulator; and with a larger terminal and holding member passage 11 leading from said ledge to the outer end of the insulating member.

The numeral 12 designates a tubular terminal and holding member located within the passage 11 and extending beyond the upper end thereof, as shown, said upper end being threaded at 13 to receive a nut for securing a supply conductor 55

thereto; and the lower end of this member is provided with means whereby it may be secured in place within said passage 11. As shown said terminal and holding member is provided with 5 lugs 14 adjacent its inner end which interlock with an internal thread within the passage 11, but any suitable means may be used for securing said member in place by an interlocking action between it and the inner wall of the 10 passage through which it extends.

The numeral 15 designates the insulated metallic electrode proper of the plug as the member 12, while it forms a part of the center wire assembly whereby current is conducted to the 15 spark gap of the plug, is herein regarded primarily as a means for holding the electrode 15 in place within the insulator and for conducting electricity to said electrode. This electrode has an enlarged head 16 which rests upon the ledge 9 and against which it is held by the terminal and holding member 12, the lower end of which abuts against said head and forms a metallic contact therewith; and the same extends through the passage 10 and beyond the lower end of the 20 insulator and into sparking relation with the grounded electrode 17 of the plug. The electrode 15 fits loosely within the passage 10 but said passage is larger than the electrode only to an extent sufficient to permit the same to be 25 conveniently assembled with the insulator and it is contemplated that there shall be no cement between it and the inner wall of the passage; from which it follows that the electrode is free to expand independently of the insulator as it 30 becomes heated, and that expansion and contraction thereof will not subject the inner end of the insulator (which expands very much less than the electrode) to strain as would be the case if the electrode was cemented in place 35 within the passage through which it extends.

The tubular terminal and holding member 12 may be made from suitable bar or tubular stock, and by the use of any machines or devices suitable for imparting to it the form and features 40 hereinbefore enumerated; although as illustrated it is preferably formed from a flat sheet metal blank by bending the same into tubular form. Such a blank is shown in Figure 2 after a series of parallel corrugations 18 have been formed at 45 one end thereof, and a series of projections 14 at the other end formed by displacing portions of the metal of the blank; after which and when the blank has been bent into tubular form its 50 sides abut with one another along the line 20, Figure 3. When finished by bending as aforesaid the corrugations 18 form the threaded end 13 of the member 12, and the projections 19 provide the holding lugs 14 whereby said member 55 is held within the passage 11 by engagement of said lugs with the thread within said passage. The end of the blank adjacent the projections 19 is formed with a projection 21 which when bent at right angles forms a closure 22 for the lower end of the tubular terminal and holding 60 member 12, and provides a better and more extensive contact between the lower end of said member and the head 16 of the electrode 15. Said blank is also formed with notches 23 which provide holes through which cement supplied to 65 the interior of said holding member under pressure may flow outward and upward along said member, thus filling the interstices between the lugs and the thread and securing a gas-tight joint at the lower end of said tubular terminal 70 and holding member. Ordinarily a sufficient

amount of cement 24 is supplied to fill both the interior of the member 12 and the space between it and the passage 11, as shown in Figure 1 of the drawing; and it will be understood that the cement is supplied as aforesaid after the member 12 has been assembled within the passage 11 and locked in place by the lugs 14, with its lower end in engagement with the head 16 of the electrode 15 to thereby hold said electrode in place within the lower passage 10.

In the making of spark plugs the porcelain or equivalent insulating members are made into substantially their final form, and the passages 10, 11 and the ledge 9 are provided, before the members are glazed and fired to vitrify them. 15 The material being quite soft it follows that the passages are often not perfectly formed, and may not always be parallel and in alignment with one another; and these and other imperfections are liable to be increased during the firing necessary to vitrify the insulators. If then the center wire of the plug is a single unitary structure so formed initially, or formed by welding the parts thereof together, the same is likely to be more or less crooked or otherwise out of shape as when 20 the axes of the parts do not coincide. Thus and unless the insulating member and center wire assembly approach perfection the assembling of the parts is more or less difficult, and is often accompanied by bending of the center wire and the 25 setting up of strains which tend to break the insulator; this breaking of the insulator or the setting up of strains tending to break it often occurring after the plug is finished as the strains may not be followed by immediate failure of the 30 insulating member. A quite common way of attempting to avoid strain in the insulating member has been to make the passage for the lower end of the single piece center wire or insulated electrode structure much larger than the part of 35 the structure which lies therein; but this necessitates the filling of the passage around said part with cement thus introducing a condition wherein longitudinal expansion of said lower part, due to the heating thereof when the plug 40 is in use, is likely to break the lower end of the insulating member; because, as will be appreciated, the material of the insulating member has a negligible coefficient of expansion and expands little if at all, whereas the lower end of the insulated electrode structure, being of metal, expands appreciably when the plug is in use and is heated by the burning gases within the combustion chamber of the engine.

In my invention and because the inner part 15 55 of the insulated electrode structure (made up of the parts 12 and 15) is independent of the outer part 12 the two may be assembled in passages which may be considerably out of alignment or otherwise lacking in perfection, without strain- 60 ing either part or setting up stresses in the insulating member. Furthermore and as will be appreciated, the passage for the inner part or electrode proper 15 may be made of less diameter than heretofore as it need be larger than 65 said part only to such an extent as to permit the same to be put in place, thus making it unnecessary to surround such inner part with cement and avoiding injury due to unequal expansion of the insulating member and said part when the plug is in use.

Furthermore and because a comparatively short length only of the lower end of the tubular terminal and holding member 12 is rigidly inter- 70 75

locked with the insulating member, the liability to injury at this part of the insulator by expansion of the short length thus interlocked, due to the heating thereof by conduction from the head 16 of the inner electrode part 15, is greatly reduced. As a matter of course the lower interlocked part of the member 12 does not attain anything like the temperature of the electrode 15 because the greater part of the heat which might otherwise be communicated to it is dissipated to the massive central part of the insulating member, and to the shell of the plug and to the engine structure; but nevertheless a decided advantage as regards the avoidance of strains in the insulating member is secured by making this interlocked part short as compared with the total length of the tubular terminal and holding member.

The fact that the head 16 of the inner electrode part 15 lies within the enlarged central part of the insulating member, as does also the lower end of the tubular member 12 which is in direct and intimate contact with said head, results in a rapid dissipation of heat from said parts to the massive central part of the insulating member and therefrom to the metallic shell or casing of the plug and to the atmosphere and engine structure, thus securing an effective conduction of heat away from the electrode part 15 and the operation of the plug at a lower temperature than

would be the case were such features of structure and arrangement of parts not present.

Having thus described and explained my invention I claim and desire to secure by Letters Patent:

1. A terminal and holding member for spark plugs comprising a flat metallic blank bent into tubular form; said member having a threaded portion at one end, and securing lugs at the other end thereof. 5

2. A flat metal blank for use in forming a tubular terminal and holding member for spark plugs; said blank having a plurality of parallel corrugations at one end, and a plurality of projections at its other end; the end of said blank 15 adjacent said projections being so shaped as to provide a closure for the open end of a terminal and holding member formed by bending said blank into tubular form. 10

3. A flat metal blank for use in forming a tubular terminal and holding member for spark plugs; said blank having a plurality of parallel corrugations at one end, and a plurality of projections at its other end; the end of said blank adjacent said projections being notched to provide cement passages, and so shaped as to provide a closure for the open end of a terminal and holding member formed by bending said blank into tubular form. 20 25
